UNITED STATES PATENT OFFICE.

GEORGE P. PAIN, OF FARGO, NORTH DAKOTA, ASSIGNOR OF ONE-HALF TO WALLACE GROSVENOR, OF CASSELTON, NORTH DAKOTA.

RAILWAY SIGNALING KIT.

No. 890,445.

Specification of Letters Patent.

Patented June 9, 1908.

Application filed July 20, 1907. Serial No. 384,703.

To all whom it may concern:

Be it known that I, GEORGE P. PAIN, a citizen of the United States, residing at Fargo, in the county of Cass and State of North Dakota, have invented certain new and useful Improvements in Railway Signaling Kits; and I do hereby declare the following to be a full, clear, and exact description of the invention, such as will enable others skilled in the art to which it appertains to make and use the same.

My invention has for its object to provide a simple, convenient and efficient railway signaling kit adapted to be carried on trains, and adapted to keep in good condition for use whenever required a supply of railway torpedoes, signaling torches and flag.

To the above ends the invention consists of the novel devices and combinations of devices hereinafter described and defined in the claims.

In the accompanying drawings which illustrate the invention, like characters indicate like parts throughout the several views.

Referring to the drawings, Figure 1 is a plan view, showing the improved kit with the lid of the case opened up, and with some parts in section. Fig. 2 is a vertical section taken through the case on the line $x^2 x^2$ of Fig. 1, showing parts broken away. Fig. 3 is a view in side elevation, showing the torpedo holder removed from the case; and Fig. 4 is a horizontal section taken on the line $x^4 x^4$ of Fig. 3.

The body of the case is in the form of a thin metal shell 1 which is preferably oval in cross section and is provided with a wooden bottom 2. At its top the case 1 is provided with a cover in the form of a cup 3 that is connected thereto at one side by a hinge 4, and at its other side is provided with a spring latch 5 that is adapted to engage with a lock lug 6 on the case 1 to hold the said cover in a closed position. The latch 5 is adapted to be easily released by outward pressure thereon from the finger.

Within the case 1 is a rigidly secured horizontal partition 7 having a central opening 8 and peripheral openings 9 and 10. The central opening 8 is preferably made oval so that it extends parallel to the surrounding wall of the case 1. An internal sheath 11 extends downward from the partition plate 7 to the bottom piece 2. This sheath 11 in cross sec-

tion is of the same form as the central opening 8 and alines therewith at its upper end. Likewise, a sheath 11^a having in cross section the same form as the opening 10 alines therewith and extends downward from the partition plate 7 to the bottom piece 2. 55

The signal torches 12 of the usual construction, indicated by dotted lines in Fig. 1, are adapted to be placed within the case and extended through the openings 9. These signaling torches, as is well known, are provided with sharpened rods at their lower ends, adapting them to be stuck in the ground or into a tie to support the torch. These sharp ends (not shown in the drawings) are adapted to be thrust against the wooden bottom 2 when the torches are placed within the case. 60

The flag 13, shown only by dotted lines in Fig. 1, is also adapted to be placed within the case and to be inserted therein through the opening 10 in the partition plate 7. 75

The standard torpedoes 14 are adapted to be placed in two stacks within a bifurcated holder made up of a dividing plate 15 having oblique in-turned retaining flanges 16 that form the holder with two longitudinally extended dove-tailed channels into which the beveled edges of the torpedoes are adapted to be slipped, as best shown in Figs. 3 and 4. At its top, the holder is shown as provided 85 with a U-shaped hand-piece 17 and at its bottom it is provided with a transverse tie bar 18 that limits the downward movement of the torpedoes. The handle 17 forms an extension of the dividing plate 15 and does 90 not prevent the easy removal of the torpedoes when they are slid out of the dove-tailed seats by upward movement toward the said hand-piece. The holder loaded with torpedoes fits closely but freely within the 95 sheath 11. When the holder loaded with torpedoes is placed within the sheath 11, the torches are placed through the openings 9, the flag 13 is placed through the opening 10, and the lid of the case is then closed, a very 100 compact kit or signaling outfit is provided and, furthermore, all of the signaling devices are well protected against snow, rain and dirt.

A device of this kind will be found very 105 serviceable for use on all railway trains.

What I claim is:

In a railway signaling kit, the combination

with a tubular case having a bottom and a
displaceable cover, of a horizontal partition
within said case having marginal perfora-
tions and a central opening, a sheath that
5 extends from said central opening of said
horizontal partition to the bottom of said
case and adapted to receive a torpedo holder,
and said marginal perforations adapted to

hold torches and a flag, substantially as de-
scribed.

In testimony whereof I affix my signature
in presence of two witnesses.

GEORGE P. PAIN.¹⁰
